[57] CLAIM

The ornamental design for a universal gauging tool, as shown.

DESCRIPTION

FIG. 1 is a front elevational view of my new design for a universal gauging tool;

FIG. 2 is a right side elevational view of my universal gauging tool, the opposite side being a mirror image;

FIG. 3 is a rear elevational view of my universal gauging tool;

FIG. 4 is a top plan view of my universal gauging tool; and,

FIG. 5 is a bottom plan view of my universal gauging tool.
